UNITED STATES PATENT OFFICE.

ERNEST L. REYNOLDS, OF ARDMORE, OKLAHOMA.

FLUID-HYDROCARBON BURNER.

1,076,449.

Specification of Letters Patent. Patented Oct. 21, 1913.

Application filed February 20, 1913. Serial No. 749,692.

To all whom it may concern:

Be it known that I, ERNEST L. REYNOLDS, a citizen of the United States, residing at Ardmore, in the county of Carter and State 5 of Oklahoma, have invented a new and useful Fluid-Hydrocarbon Burner, of which the following is a specification.

The present invention relates to improvements in fluid hydrocarbon burners, one object of the present invention being the provision of a simple form of burner, which is especially adapted for domestic use for introduction within cooking ranges or other stoves, and whereby a heavy or a light oil 15 may be used.

With the foregoing and other objects in view which will appear as the description proceeds, the invention resides in the combination and arrangement of parts and in the 20 details of construction hereinafter described and claimed, it being understood that changes in the precise embodiment of the invention herein disclosed can be made within the scope of what is claimed without departing 25 from the spirit of the invention.

In the drawings—Figure 1 is a vertical central sectional view through the complete burner, the induction pipe and valve being shown in elevation. Fig. 2 is a cross section 30 taken on line 2—2 of Fig. 1. Fig. 3 is a cross section taken on line 3—3 of Fig. 1. Fig. 4 is a view illustrating a modified form of induction nozzle or jet.

Referring to the drawings, the numeral 1 35 designates a tubular cylinder, which may be made integral or in separate parts, and is adapted to be disposed above a drip pan 2, so that any surplus oil will flow therein, and yet not interfere with the draft through 40 the member 1. Formed about the member 1 intermediate of its ends is an oil conducting annular chamber 3, which is in communication at all times with the valve controlled 45 oil supply pipe 4. Where the oil is a light oil, the same will be fed by gravity into the annular chamber 3 and where the same is a crude or heavy oil, the same may be fed under pressure as is found necessary.

There is formed in the member 1 adjacent 50 and concentric to the chamber 3, the recess 5, which provides the lip 6 for the direction of the sprayed oil from the radially disposed inwardly discharging nozzles or jets 7, there being four shown in the present instance, although any number may be employed. The inner wall of the recess 5

tapers upwardly as shown, while the inner wall of the projecting portion 6 terminates in the same circumferential line as the inner circumference of the tubular member 1. 60

From the foregoing description, taken in connection with the drawings, it is evident that an exceedingly simple and durable domestic burner is provided, the same consisting of few parts and presenting its nozzles 65 7, so that the same may be readily cleaned and kept freely open at all times for the proper passage of the oil therethrough.

In use, the member 1 is disposed vertically, as shown in Fig. 1, and the oil is permitted to flow so as to partially or entirely fill the recess 5 and a greasy saturated waste or paper is placed within the pan 2 below the lower end of the member 1 and ignited. When the oil within the recess 5 is properly ignited, the valve or conduit 4 is opened to properly permit of the introduction of the sprays of oil through the nozzles 7 to be properly gasified and ignited within the bore of the tubular member 1 so that the 75 flame therefrom will be directed to the upper end, as is clearly evident. The nozzles 7' may also be inclined upwardly so as to insure the proper direction of the flame and create to a great extent the proper draft 80 for drawing into the lower end sufficient air to supply the necessary oxygen to produce 85 a blue flame, all as is illustrated in Fig. 4.

The recess 5 provides a means under ordinary circumstances to retain any drip 90 from the nozzles or jets 7, and prevents the passage thereof into the drip pan 2, and also provides to a great extent the vaporizing chamber for the oil during the operation of the burner as the complete body 1 is heated 95 as well as the annular chamber 3 by the burning of gasified oil.

The present device is readily applied within the combustion chamber of a range or other domestic stove, and being of simple 100 construction, the same is readily installed and as before stated kept in working condition.

What is claimed is:

1. A fluid hydrocarbon burner, including 105 a vertically disposed tubular member provided intermediate of its ends with an internal fluid receiving recess provided with an upwardly inclined mouth disposed entirely within the walls of the member, and an oil 110 distributing chamber embracing the member adjacent the recess and provided with a plu-

rality of jet apertures in communication with the interior of the member at points above the lower rim of and within the recess.

6. 2. A fluid hydrocarbon burner, including a tubular member open at both ends and provided intermediate of its ends with a recess formed in the inner wall thereof, the rear wall of which is inclined to provide a relatively wide mouth thereto, and an oil distributing chamber encircling the member adjacent the recess and having a plu-

rality of jet apertures leading therefrom through the wall of the tubular member and terminating through the inclined wall of 15 the recess.

In testimony that I claim the foregoing as my own, I have hereto affixed my signature in the presence of two witnesses.

ERNEST L. REYNOLDS.
